UNITED STATES PATENT OFFICE.

LORENZO EVANS, OF CHARITON, IOWA.

LOCK.

1,177,501.

Specification of Letters Patent. Patented Mar. 28, 1916.

Application filed November 10, 1914. Serial No. 871,355.

To all whom it may concern:

Be it known that I, LORENZO EVANS, a citizen of the United States, residing at Chariton, in the county of Lucas and State of Iowa, have invented new and useful Improvements in Locks, of which the following is a specification.

The present invention relates to improvements in locks.

10 In carrying out my invention it is my purpose to produce a lock comprising few parts and wherein the employment of springs is entirely obviated.

It is also my aim to construct a lock 15 wherein the bolt is shot by a weighted member and to provide mechanism which acts upon said weighted member to slide the bolt to an unlocking position.

It is a still further object of the invention 20 to produce a lock having its bolt normally projected by a weighted member, and means for actuating the said weighted member, a slideable tumbler being arranged within the path of contact with the rear of the bolt, a 25 weighted detent coöperating with the tumbler to prevent the movement thereof, and means being provided for actuating the detent to bring the same out of engagement with the tumbler and to slide the said tumbler to permit of the actuation of the locking bolt.

A further object of the invention is to provide a lock wherein the bolt may be actuated by the usual knob from either side of 35 the lock; wherein the bolt may be locked and the locking mechanism actuated by a key from either side of the lock or whereby said actuating mechanism will be operated from only one side of the lock.

40 In the drawings: Figure 1 is a perspective view of a lock constructed in accordance with the present invention, Fig. 2 is a side view of the same, Fig. 3 is an elevation with the back plate of the lock casing removed, 45 the tumbler having been moved to permit of the sliding of the bolt to an unlocking position, Fig. 4 is a similar view but showing the tumbler moved into contact with the bolt and locked in such position, the key hole or 50 curtain plate covering the key hole so that the bolt and detent may be actuated only from one side of the lock, Fig. 5 is a similar view but showing the curtain plate moved away from the key hole to permit of the insertion of a key and the actuation of the tumbler from the second side of the lock,

Fig. 6 is a sectional view on the line *a—a* of Fig. 2, Fig. 7 is a sectional view on the line *b—b* of Fig. 2, Fig. 8 is a sectional view on the line *c—c* of Fig. 2, Fig. 9 is a sectional view on the line *d—d* of Fig. 2, Fig. 10 is a perspective view of the bolt, Fig. 11 is a similar view of the bolt projecting lever, Fig. 12 is a similar view of the bolt locking member or tumbler, Fig. 13 is a perspective view of the detent for the tumbler, Fig. 14 is a perspective view of the knob shaft, Fig. 15 is a similar view of the combined tumbler actuating member and key hole shield or curtain which is operated from the interior 70 of the house to which the lock is attached.

Referring now to the drawings in detail, the numeral 1 designates the lock casing which is of the usual hollow rectangular construction, and which is provided with an 75 outer side plate 2 and an inner side plate 3. If desired, one of the said plates may be integrally formed with the casing.

The numeral 4 designates the locking bolt which is mounted in suitable bearings 5 in 80 the casing 1 and which projects through a suitable opening in the face plate of the casing. The bolt 4 adjacent its inner end is provided with a slot 6 which preferably extends all the way through the said bolt, so 85 that the same may be withdrawn and reversed, for a purpose which will be readily understood.

The numeral 7 designates the bolt projecting member or lever. This member includes 90 a vertically disposed arm 8, which has its end arranged within the slot 6 of the bolt, a horizontally disposed arm 9 which has its extremity weighted, as at 10.

The numeral 11 designates a pin which 95 passes through a suitable opening at the juncture of the arms 8 and 9 of the members 7 and is received within a suitable boss in the plate 2.

By an arrangement as above described, 100 it will be noted that the weighted end 10 of the substantially L-shaped operating lever 7 will swing the said lever upon the pivot pin 11, causing the end of its arm 8 to contact with one of the end walls provided by the slot 6 and so project the bolt through the casing. The L-shaped operating lever 7 has its arm 9, approximately 105 centrally provided with a round boss 12.

The plates 2 and 3 are provided with 110 alining openings for the reception of the opposite ends of a shaft 13, the ends of the

shaft projecting through the openings being provided with suitable knobs 14 and 15, and the shaft 13 is centrally provided with a lateral portion 16 which is disposed directly beneath or in contact with the round boss 12 of the bolt projecting lever 7. It will be understood that when either of the knobs 14 or 15 are turned the lateral member 16 will act upon the boss 12, swinging the weighted end 10 of the throw lever 7 upward of the casing 1, and consequently drawing the bolt 4 to within the casing. When pressure upon the knob is released, the weighted member 10 will return the lever 7 to its initial position and the bolt will again be projected through the opening in the face of the casing 1, while the lateral or swinging member 16 of the shaft 13 will be returned to its initial horizontal position.

It is, of course, obvious that some means must be employed for retaining the bolt in its locking position, and to provide for this I employ a dogging bolt 17 which is loosely mounted in suitable bearings 18 and 19.

The dogging bolt 17 comprises a substantially rectangular member and is provided upon its underface with a notched lug 20, the said lug, when the tumbler is in contacting engagement with the inner end of the bolt 4, being arranged directly above the key hole slot 21 formed in the outer plate 2. The bolt 17 is provided upon its underface with a second transverse notched lug 22, the same being suitably spaced from the notch 20. The dogging bolt 17 upon its upper face is provided with a pair of transverse slots which are indicated by the numerals 23 and 24 respectively, and the numeral 25 designates a weighted detent which has its tongue received within the slot 24 when the tumbler is in contacting engagement with the locking bolt 4 and in the slot 23 when the dogging bolt is moved away from the sliding bolt. The detent 25 has secured thereto a longitudinally extending arm 26, the same being pivoted to the plate 2, as at 27. The arm 26 is arranged horizontally straight from its pivot 27 to the part thereof arranged over the key hole slot 21, and is from thence inclined upwardly to its connection with the detent 25, as clearly shown in the drawings, the purpose of which arrangement will now be described.

A key, indicated by the numeral 28, is employed for unlocking the door from the exterior of the door upon which the lock is arranged or from the side thereof provided with the plate 2. This key has its shank provided with an extending lug or ward 30, which is of a slightly greater length than the bit 29 of the key. The ward 30 is arranged at an angle with relation to

the bit 29, but the key hole opening is of a size to admit of the insertion of both the bit and ward. The key, after being inserted through the key hole opening, is turned in an unlocking direction. The ward 30 will first contact with the straight portion of the arm 26 raising the detent 25 out of the slot 24 and permitting the bit of the key entering the notch of the lug 20 and to contact with the inner finger 20^a provided by the said notch to slide the dogging bolt away from the locking bolt to permit of either of the knobs being operated to actuate the projecting lever 7 to cause the withdrawal or inward movement of the locking bolt 4. When the dogging bolt has been moved, by the bit of the key, the proper distance, the weighted detent 25 will have been released by the ward 30 of the key, permitting the engaging member or tongue 85 of the same entering the transverse slot 23 of the dogging bolt, thus holding the dogging bolt in this position. When the dogging bolt is to be moved to engage with and lock the locking bolt 4, the key is turned in a reverse direction and its bit will contact with the second finger 20^b provided by the notch in the lug 20. It is to be understood that the distance between the fingers 20^a and 20^b is sufficient to allow the bit of the key moving in the notch without contacting with the finger 20^b until after the ward 30 engages with the arm 26 of the detent to raise the same out of the notch 23, and to permit the same to drop by gravity in the notch 24 when the dogging bolt has been moved to said locking position.

In order to screen or obstruct the key hole 21 and permit of the locking bolt being unlocked only from the interior of the house I provide a latch device illustrated in detail in Fig. 14 of the drawings. The latch includes a shank 31 that finds a bearing in an opening provided in a boss 33 in the inner escutcheon plate and an opening 33 in the side plate 3 of the lock casing, and if necessary, the end of the shank may be received in an opening in the plate 2 of the said lock casing. The shank is provided with a removable head 32 and the portion thereof received in the lock casing with a bit 36 and a throw arm or ward 37 which is arranged at an angle with relation to the bit. Also the shank is provided with an angularly arranged flat plate 38 that is disposed to cover the outer key hole opening in the block casing when the latch is turned in one direction. The bit 36 is adapted to be received in the notch of the lug 22 when the dogging bolt is to be moved into contacting engagement with the locking bolt and with the opposite finger 22^b when the latch is turned in an opposite direction to slide the dogging bolt out of engagement with the 120 125 130

locking bolt. The distance between the fingers 22^a and 22^b is sufficient to permit of the bit 36 engaging with one of the said fingers to slide the bolt, irrespective of the position to which the said dogging bolt has been moved by the key, and as a consequence the bit of the latch is of a greater length than the bit of the key. The throw arm or ward 37 is of a length to contact with the angular portion or arm 26 of the detent 25 to raise the said detent out of one of the notches of the dogging bolt to permit of the sliding of said dogging bolt by the bit of the latch and to disengage the arm of the said detent to permit of the same again engaging in one of the notches of the dogging bolt after the dogging bolt has been moved the desired distance by the latch. This arrangement of the latch is such, it will be noted, as to not interfere with the operation of the key, when the shield 33 has been moved to uncover the key hole opening as illustrated in Figs. 3 and 5. The removable head 32 is provided with a notch 40 and the boss 33 is provided with a similar notch 39, and these notches are adapted to register when the shield is brought over the key hole opening to indicate to the occupant of the house that the said opening is closed and that the locking bolt is in locked position.

Having thus described the invention, what I claim is:

1. In a lock having a locking bolt, weighted means for moving the bolt in one direction, and means comprising mechanism for actuating the weighted means to move the bolt in a second direction, the lock casing having a key hole opening upon one of its sides, and a key having its bit provided with a ward adapted to be received in the opening, a dogging bolt arranged above the key hole opening to the rear of the bolt, said

tumbler having its underface provided with spaced notches, one of which being arranged over the key hole opening when the tumbler is moved to contact with the lock, the said dogging bolt having its upper face provided with spaced slots, a weighted detent engaged within one of the slots, an arm connected with the detent and pivotally secured in the lock casing, a key forming a permanent member of the lock, and having its bit provided with a ward and the ward being arranged within the path of contact of the pivoted arm of the weighted detent, and the stem of the last mentioned key being provided with a shield which, when the key is rotated to cover the key hole opening.

2. In a lock, a locking bolt, means for operating the same, of a dogging bolt arranged to the rear of the locking bolt, the lock having an opening for a key for actuating the dogging bolt, a weighted detent to coengage with the dogging bolt to lock the same in contact with the locking bolt or out of such contact, said detent including a pivoted arm, a latch spindle journaled in the lock casing, a removable head for the spindle, a bit upon the spindle for engaging with the dogging bolt to actuate the latter, a ward upon the spindle to contact with the arm of the detent to bring the detent out of engagement with the dogging bolt when the said dogging bolt is engaged by the bit of the spindle, and a shield upon the said spindle for closing the key hole opening when the spindle has been turned to move the dogging bolt into contact with the locking bolt.

In testimony whereof I affix my signature in presence of two witnesses.

LORENZO EVANS.
